UNITED STATES PATENT OFFICE.

WILLIAM H. BUCKINGHAM, OF MOUNT TAMALPIAS, AND HAROLD S. JOHNSON, OF MILL VALLEY, CALIFORNIA, ASSIGNORS TO HERCULES MOTOR PATENTS INC., OF SAN FRANCISCO, CALIFORNIA, A CORPORATION OF CALIFORNIA.

WORM-DRIVE FOR RAILWAY-CAR TRUCKS.

1,216,064.

Specification of Letters Patent. Patented Feb. 13, 1917.

Application filed August 21, 1916. Serial No. 116,014.

To all whom it may concern:

Be it known that we, WILLIAM H. BUCKINGHAM and HAROLD S. JOHNSON, citizens of the United States, residing at Mount Tamalpias and Mill Valley, respectively, in the county of Marin and State of California, have invented certain new and useful Improvements in Worm-Drives for Railway-Car Trucks, of which the following is a specification.

The present invention relates to improvements in trucks for railway cars, and more particularly to a type of truck for use in connection with self-propelled railway cars, and where it is desirable, employs an internal combustion engine or other motor, mounted on the car frame as the source of power and to drive the truck wheels.

The principal object of the invention is to provide a simple, efficient and direct worm drive for the vehicle truck supporting wheels, and by the employment of which, the drive chains and beveled gears now in use, are dispensed with. To provide a structure wherein a worm drive is employed for transmitting power to the truck wheels, one which is comparatively noiseless in its operation, and where the upkeep is reduced to a minimum.

With the above mentioned and other objects in view, the invention consists in the novel construction and combination of parts hereinafter described, illustrated in the accompanying drawings and set forth in the claims hereto appended; it being understood that various changes in the form, proportion, size and minor details of construction, within the scope of the claims may be resorted to without departing from the spirit or sacrificing any of the advantages of the invention.

To more fully comprehend the invention, reference is directed to the accompanying drawings, wherein—

Figure 1 is a view in side elevation of a self propelled railway car with an embodiment of our improved device illustrated in connection therewith.

Fig. 2 is a central sectional view, longitudinally of the car.

Fig. 3 is an enlarged detail plan view of the preferred form of drive, several parts thereof, being broken away to more fully

illustrate the interior mechanism of the drive.

Referring more particularly to the several views of the drawings wherein like characters of reference designate corresponding parts, 1 indicates a suitable car frame supported at its front end in any suitable manner, as by the pivotally mounted pilot truck 2, having rail running wheels 3, and said frame is adapted to carry a propelling motor 4, preferably of the internal combustion engine type.

Mounted adjacent the opposite end of the frame 1 from the truck 2, are the pedestals 5 of any suitable construction and the same are arranged in pairs opposite each other to receive the bearing boxes 6, into which project the bearing ends of the solid axles 7, each provided with the usual rail running wheels 8. Keyed, as at 9 to rotate with each axle 7 and arranged centrally thereof, between the wheels 8 are the worm gears 10, each of which is positioned within a housing 11. A torsion rod 12 connected at its opposite ends to the respective housings 11, through the vertical pivots 13, prevents the housings from rotating with the axles and wheels, and at the same time permits of an independent horizontal swinging movement of each axle 7 within the limits permitted by the pedestals. Suitable bearings 14 reduce friction between the sides of the gears 10 and the respective housings 11.

A worm pinion 15 is mounted to rotate on a horizontal axis in bearings 16 in the upper portion of each housing 11, and one of said worm pinions intermeshes with each of said worm gears 10 to drive the same. The rear end of the worm pinion 15 of the forward axle, and the forward end of the worm pinion 15 of the rear axle, are interconnected through the universal joints 17 with a shaft 18 which drive the same in unison. The universal joints 17 are positioned one in vertical alignment with each of the pivots 13 of the torsion rod to permit the independent swinging of the axles.

The forward end of the worm pinion 15, associated with the front axle, is connected with the engine 4 through the universal joints 17 by a drive shaft 19. To compensate for the movement of the axles relatively to the frame 1 due to the resiliency of the

supporting springs not shown, a sleeve joint 21 is provided in the drive shaft 19, and if necessary a sleeve joint 22 may be mounted in the shaft 18. It will be apparent that we have provided a worm drive for railway cars which is simple in construction and silent in its operation, and may be attached with little expense to car-wheel axles as now constructed providing a four wheel drive for railway cars carrying their own source of power.

Having thus described our invention, what we claim is:

1. A driving truck for railway cars comprising a frame, a pair of oppositely disposed pedestals mounted thereon, a pair of solid axles provided with rail running wheels and a worm driving gear carried by said axles, a housing inclosing each of said worm driving gears, a torsion rod pivotally connecting said housings, a worm driving pinion rotatably mounted in each of said housings and coöperating with the respective worm gear therein, and a shaft connecting said worm driving pinions, whereby the same will be caused to rotate in unison.
2. A driving truck for railway cars comprising a frame a pair of oppositely disposed pedestals mounted thereon, solid axles provided with rail running wheels and a worm driving gear carried by said axles, a housing inclosing each of said worm driving

gears, means for preventing the rotation of the housing with their respective axles, a worm driving pinion rotatably mounted in each of said housings for coöperating with the respective worm gear therein, and a shaft connecting said worm driving pinions whereby the same will operate in unison.

3. A driving truck for railway cars comprising a frame, a source of power carried thereby, a pair of oppositely disposed pedestals mounted thereon, solid axles provided with rail running wheels and a worm driving gear carried by each axle, a housing inclosing each of said worm driving gears, a torsion rod for pivotally connecting each of said housings to prevent the rotation thereof, a worm driving pinion rotatably mounted in each of said housings for coöperating with the respective worm gear therein, a shaft connecting said worm pinions to cause the same to rotate in unison, and a connection from said source of power, and one of said worm driving pinions.

In testimony whereof we have signed our names to this specification in the presence of a subscribing witness.

WILLIAM H. BUCKINGHAM.
HAROLD S. JOHNSON.
